William Gerrish, of Poland, State of Maine
Letters Patent.

The schedule referred to in this Letter Patent and making part of the same, containing a description in the words of the said William Gerrish himself of his improvement in the crimping form for crimping Boot-fronts.

To all to whom these presents shall come
Be it known, that I, William Gerrish, of Poland in the County of Cumberland, and State of Maine Shoemaker, have invented a new and useful improvement in Manufacturing Boots, being a machine to crimp or form the boot-front called a crimping form, with the following as a full and exact description of the construction and operation of said machine as invented or improved by me A. in the annexed drawing A. & 1 representing the front of the crimping form over which the boot-front is placed and fastened by tacks to B. & C. the back and front pieces of the crimping form B. occupies the back piece and C. the foot piece of the crimping form to each of which the boot-front is fastened by tacks D. & E. A. represents four slides moving and made fast in the front piece A. and passing through the back piece B. and the foot piece C. of the crimping form, on which the back piece B. and foot piece C. move and by which their movement is regulated, and the form is kept in shape, as the back piece B. and the foot piece C. are extended from the front piece A. by thumb screws, S 1 S 2 S 3 representing thumb screws of iron passing through B. and working through an iron nut fixed to the inside of B. and passing against an iron nut fastened to the front piece A. S 4 & S 5 represent two other thumb screws passing through the front piece C. and an iron nut on the inside of C. and passing against an iron nut fastened to the front piece A. The boot-front being drawn

over the front piece A, and fastened to the back piece B, and the foot piece C, of the crimping form by tacks B & C are then extended from A. by turning the thumb-screws S. 1, S. 2, S. 3, S. 4, and S. 5. until the boot-front is brought into shape or from crimping the leathers and tacks which are used. the process of the crimping form thus far is described as made of hard wood and it may be used to great advantage in the manner without any alteration. But it is still better and contemplated to be used by adding a thin plate of iron or brass which is fastened to the front piece A, marks H, H, in drawing arranged at A. 2 within which back piece B and foot piece C enter. The description of the crimping form in drawing A. 1 - gives the full description of drawing A. 2 excepting the brass or iron plate which is fastened to the front piece A, as a brace and is marked H. H. the leather of the boot-front is drawn over the front piece A, & the plate H. H. and fastened to the wood or back piece B, and foot piece C, by tacks the extension of which (B & C) by the thumb-screws from A. crimp or forms the boot-front. This operation in forming the boot-front is much quicker than any other to my knowledge in use, and the advantage is that the boot-front is brought into form much more round than by the usual process the leather being kept of nearly equal thickness in all its parts much more than it is in any other process I have known to be used the expense of the crimping form is so trifling and the time saved by it is great and the manner by which the boot-front is formed is so much more perfect that I am persuaded it will prove to be highly beneficial. - Polana August the 17th 1835
